METALWORKING MACHINE

Frank H. Le Jeune, Detroit, Mich., assignor to
 Kelsey-Hayes Wheel Company, Detroit, Mich.,
 a corporation of Delaware

Application February 15, 1937, Serial No. 125,866

16 Claims. (Cl. 153—48)

This invention relates generally to metal working machines and refers more particularly to apparatus for forming cupped elements from sheet metal blanks.

One of the principal objects of this invention consists in the provision of apparatus of the character set forth requiring less material power to form relatively deep-cupped elements from sheet metal blanks and capable of more expeditiously and economically forming cupped elements with less waste resulting from tearing or wrinkling of the metal during the drawing operation employed in the past. In accordance with this invention, provision is made in the apparatus for fashioning a cupped element from a pre-formed annulus by merely turning one end of the annulus inwardly and by maintaining the metal under compression as it is turned inwardly. This renders it possible to more expeditiously form cupped elements of greater depth without wrinkling or otherwise deforming the metal.

With the above in view, the present invention contemplates apparatus including a die having a portion adapted to receive one end of a tubular blank and having an inwardly curved portion effective upon movement of the blank toward the die to flare said end of the blank inwardly. In the present instance, the blank is initially yieldably urged toward the die by a member engageable with the edge of the blank opposite the end to be formed and is subsequently positively moved toward the die by a punch movable into the blank to prevent deformation of the latter during the forming operation.

Another advantageous feature of this invention resides in the provision of apparatus of the above type wherein the side walls of the die have a sliding fit with the exterior surface of the blank and wherein the dimension of the punch is such as to have a sliding fit with the interior surface of the blank.

A further object of this invention consists in the provision of apparatus wherein the member acting on the blank to move the latter toward the die also serves to strip the blank from the punch upon initial return movement of the latter.

Still another feature of the invention consists in the provision of a sectional die having one section for receiving the blank and having another section in the form of a pad movable in timed relation to the stripping operation to eject the completed article from the first die section.

The foregoing, as well as other objects, will be

made more apparent as this description proceeds, especially when considered in connection with the accompanying drawings, wherein:

Figure 1 is a sectional view through the apparatus showing the several parts thereof in the positions the same assume just before the ram reaches its upwardmost position;

Figure 2 is a sectional view similar to Figure 1 showing the parts in an intermediate position;

Figure 3 is a sectional view illustrating the parts in the position the same assume upon completion of the forming operation;

Figure 4 is a sectional view taken substantially on the line 4—4 of Figure 2;

Figure 5 is an enlarged sectional view through the fluid pressure controlling valve for the pad of the die; and

Figure 6 is a perspective view of an annular blank of the type fashioned by the machine to form a cupped element.

In general, the machine forming the subject matter of this invention is in the form of a press having a vertically reciprocable ram 10 and a punch 11 secured to the ram for movement as a unit therewith. The lower end of the punch 11 cooperates with a die 12 to curl the lower end of the annular blank A in Figure 6 to the contour shown in Figure 3. The die 12 comprises a ring 13 and a pad 14 supported for reciprocation relative to the ring 13 on the axis of the ram 10. Upon reference to Figure 3, it will be noted that when the pad 14 is in its lowermost position, the top surface thereof forms a continuation of the inner side wall surfaces of the ring or die section 13, and when raised through the die ring 13 to the position thereof shown in Figure 1, it ejects or lifts the finished product to a position above the die 12, where it may be conveniently pushed out of the machine by the operator. After the finished product has been removed from the machine, another annular blank A is placed over the pad 14 while the latter is in its raised position and the lower end of the blank is piloted into the die section 13 by the outwardly flared upper end of the die. The arrangement is such that when the ram is again moved downwardly, the inwardly curved lower end of the punch enters the upper end of the blank and a yielding pressure is exerted on the upper edge of the blank tending to move the latter downwardly into the die. The yielding pressure is exerted by the stripper 15, to be presently described, and initially serves to cooperate with the punch in aligning the blank with the die. In this connection, it will be noted that the

internal diameter of the annular surface of the ring 13 approximates the external diameter of the blank so as to have a sliding fit therewith, and the outside diameter of the punch 11 approximates the inside diameter of the blank in order to cooperate with the ring 13 in effectively holding the blank from deformation during the forming operation.

In order to prevent the cupped element from adhering to the punch 11 upon upward movement of the latter by the ram 10, provision is made for stripping the cupped element from the punch as soon as the ram 10 starts its return movement. The stripper is designated generally in the several views by the reference character 15 and is shown in Figures 1 to 4, inclusive, as being interposed between the ram 10 and die 12. Briefly described, the stripper comprises a spider 16 and a ring 17 concentrically disposed with respect to the axis of reciprocation of the punch 11. The spider is shown in Figure 3 as positioned directly above the punch 11 and as having circumferentially spaced depending projections secured to the ring 17 to provide a unitary construction.

As will presently be set forth, the spider together with the ring are supported in the assembly for vertical movement relative to the punch 11 and the internal diameter of the ring 17 is predetermined to slidably receive the punch. In view of the fact that the punch is adapted to slide into the upper end of the blank A, it follows that the stripper ring 17 abuts the upper edge of the blank. In the present instance, a constant yielding pressure is exerted on the spider 16 tending to move the blank into the die 13 with the punch, and this pressure is subsequently replaced by positive engagement of the ram with the stripper ring so that continued downward movement of the ram effects a corresponding movement of the blank into the die as a unit with the punch.

Upon reference to Figure 1, it will be noted that the ring 17 is normally held in its lowermost position relative to the punch by means of a plurality of fluid pressure cylinders 23 acting upon the upper end and of a pin 24 having the lower end thereof engageable with the spider 16 of the stripper. As indicated above, however, the stripper is capable of vertical movement relative to the punch and for accomplishing this result the stripper is connected to the ram through the medium of a lost motion connection. This connection is shown in Figure 3 as comprising a ring 25 secured to the underside of the ram 10 in concentric relation to the stripper ring 17 and slidably engaging the outer surface of the latter. The bottom of the ring 25 is provided with an inwardly extending annular projection 25' engageable with an outwardly extending annular shoulder 17' on the stripper ring 17 to raise the stripper 16 with the ram 10, subsequent to the stripping operation. In this connection, it is to be noted that the stripper is raised by the ram against the action of the fluid pressure in the cylinders 23 and, for this reason, a fluid is selected which is compressible.

With the brief description of the machine noted above, it will be apparent that an annular blank A to be cupped is placed over the pad 14 when the latter is in its raised position shown in Figure 1. As the ram continues to move upwardly from the position shown in Figure 1, the pad 14 is returned to its lowermost position in cooperative relation to the die ring 13 by means of a fluid actuated piston controlled by a valve

26 shown in Figure 1 as being actuated by a cam 27 secured to the ram 10 for movement as a unit therewith. The ram is then moved downwardly and initial movement in this direction causes the rounded lower end of the punch 11 to move into the upper end of the blank A. At approximately the same time the stripper ring 17 engages the upper edge of the blank and positions the latter in the die. As the punch 11 progresses downwardly toward the die 12, the stripper ring 17 exerts a pressure on the upper end of the blank A and telescopes the lower end of the blank into the die. It will, of course, be understood that the pressure exerted upon the upper edge of the blank depends upon the constant pressure in the cylinders 23 and this pressure acting through the stripper ring 17 causes the lower end of the blank to flare inwardly in accordance with the curvature of the die 12. As the resistance to downward movement of the blank A by the stripper ring 17 exceeds the pressure acting on the stripper ring, the punch 11 continues to move downwardly, relative to the stripper ring, in sliding contact with the inner surface of the blank A until the upper surface 30 of the stripper ring 25 contacts with the bottom surface 31 of the punch holder 32, whereupon continued downward movement of the punch effects a corresponding downward movement of the stripper ring to complete the forming operation. During this forming operation the curved surface of the die maintains the metal of the blank under compression and wrinkling of the metal is avoided.

When the forming operation is completed, the punch 11 is raised by the ram 10 relative to the stripper ring 17 until the inwardly extending projection 25' on the ring 25 of the ram engages with the annular shoulder 17' on the stripper ring, whereupon the latter is raised as a unit with the ram. It is to be noted, however, that during initial upward movement of the punch 11 relative to the stripper ring 17, the latter functions to strip the cupped element from the punch 11, so that this cupped element is retained in the die 12.

Upon completion of the stripping operation, the valve 26 is actuated by the cam 27 to raise the pad 14 through the medium of the fluid pressure cylinder 28. As the pad 14 is raised, the same ejects the cupped element from the die 12 and permits the cupped element to be pushed out of the press by the operator. Another annular blank A may then be immediately positioned around the pad in the die 12 and the foregoing operation repeated.

Having described in general the operation of the press, reference will now be made more particularly to the construction of the several parts involved. In detail, the press briefly described above comprises a casting 33 supported in any suitable manner on a bolster plate 33' and having diametrically opposed upwardly extending guide pins 34 adapted to slide in bushings 35 secured in a bore 35' in the punch holder 32. The arrangement is such as to accurately guide the punch plate 32 throughout movement thereof and to insure proper registration of the punch 11 with the die 12. Upon reference to Figure 3, it will be noted that the top surface of the casting 33 is recessed, as at 36, to receive the lower end of the die section 13 and thereby accurately positions this die section relative to the punch 11. In the present instance, the die section 13 is secured to the casting 33 in the recess 36 by means of studs 37 and is provided with an open-

ing 38 in the center thereof aligned with a similar opening 39 through the casting 33.

The pad 14 is supported in the aligned openings aforesaid by means of the fluid pressure cylinder 27 carried by the bolster plate 33' and the upper end of the pad has a hardened plate 40 secured thereto for cooperation with the annular section 13 to form the die 12. The pad 14 is positioned with the plate 40 forming a continuation of the inner surface of the die 12 by engagement of the lower end 41 of the pad with the top surface of the bolster plate 33' having a central opening therethrough for receiving a connecting rod 42. The upper end of the connecting rod is secured to the lower end of the pad 14 and the opposite end of the connecting rod is secured to a piston 43 reciprocably mounted in a vertical cylinder 44 secured in any suitable manner to the underside of the bolster plate 33'. The cylinder is of the double-acting type having the lower end communicating with a conduit 45 and having the upper end communicating with a conduit 46. The conduits, in turn, alternately communicate with a fluid pressure supply line 47 through the medium of the valve 26, shown in detail in Figure 5. This valve is of the two-way piston type having a cylinder 48 and having a piston 49 normally urged to its forwardmost position by means of a spring 50. The piston is ported and in its forwardmost position establishes communication from the supply line 47 to the conduit 46 through the port 51 in the piston. Also, in the above mentioned position of the valved piston 49, the exhaust port 52 in the piston communicates with the conduit 45 so that as fluid pressure is discharged into the upper end of the cylinder 44 from the conduit 46, the fluid pressure below the piston is exhausted through the conduit 45. This permits the pad 40 to assume its lowermost position shown in Figure 3, wherein the hardened plate 40 cooperates with the die ring 13 to form the die 12.

The valved piston 49 is moved rearwardly against the action of the spring 50 by means of the cam 27 secured to the punch holder 32 in the manner clearly illustrated in Figure 3. The arrangement is such that when the punch holder 32 is moved upwardly by the ram, the valved piston 49 is moved rearwardly by the cam 27 to a position wherein communication is established between the supply conduit 47 and the conduit 45 through another port 53 in the piston. At the time the port 53 in the piston communicates with the conduit 45, the exhaust port 54 in the piston communicates with the conduit 46 so that as fluid under pressure is admitted to the cylinder 44 at the underside of the piston to raise the pad, the fluid in the cylinder 44 above the piston is exhausted. The valved piston is maintained in the latter position by the cam 27 until this cam is moved by the ram to a position above the valve actuator 55, whereupon the valved piston 49 is actuated by the spring 50 to return the pad 14 to its lowermost position with respect to the die 12. In this connection, it is to be noted that when the ram 10 is moved downwardly, the cam 27 is rendered inoperative to actuate the valve 26 and, as a consequence, the lowermost position of the pad 14 is not disturbed. This is accomplished herein by forming downwardly inclined slots 56 in the cam and by supporting the cam on the punch holder 32 through the medium of pins 57 extending through these slots. Upon reference to Figure 3, it will be noted that the long axes of the slots 56 are substantially

parallel to the upper cam face 58 on the cam 27 and are substantially normal to the lower cam face 59 on the cam 27. As a consequence, when the punch holder is raised from its lowermost position, shown in Figure 3, a sufficient distance to engage the valve actuator 55 with the upper face 58 on the cam 27, the force tending to move the cam 27 inwardly, instead of actuating the valved piston 49, is taken directly against the pins 57, with the result that the cam 27 retains its outermost position and the valved piston 49 moves against the action of the spring 50. On the other hand, when the valve actuator 55 is in contact with the lower cam face 59 on the cam 27, downward movement of the punch holder 32 exerts a force on the cam in the direction of the long axes of the slots and merely slides the cam 27 inwardly, without disturbing the forwardmost position of the valved piston 49.

The ram 10 comprises a vertically reciprocable member 60 driven in any suitable manner and connected to the punch holder 32 by means of a punch head 61. Upon reference to the several figures, it will be noted that the underside of the punch holder 32 is formed with a recess 62 therein having angularly spaced depending projections 64 abutting the top surface of the punch 11 and secured to the latter by means of the stud bolts 65. Thus, the punch 11, holder 32, and head 61 move as a unit with the ram.

The punch 11 comprises an annular body member 65 and a plate 66 secured to the upper surface of the body member by means of the studs 67. The external diameter of the punch is such as to have a sliding fit in the blank A, and the lower end of the body section 65 is fashioned to correspond to the contour of the die 12 so as to cooperate with the latter in forming the cupped portion at the lower end of the blank.

The stripper 15 comprises a spider 16 located in the recess 62 of the punch holder and having the arms thereof extending between the angularly spaced depending projections 64 on the punch holder. The free ends of the spider are formed with depending projections 69 adapted to abut the top surface of the stripper ring 17 and to be secured to the latter by means of the studs 70. The stripper ring 17 is concentrically disposed with respect to the punch 11 and the internal diameter thereof is such as to slidably engage the side walls of the punch. Upon reference to Figure 3, it will be noted that the stripper ring 17 is disposed between the underside of the punch holder 32 and the top surface of the die section 13, and is normally urged in a direction 55 toward the die 12 by means of fluid under a constant pressure acting through the cylinders 23. In detail, the cylinders 23 are supported in a vertical position on the head 61 at diametrically opposite sides of the latter and the lower ends of the cylinders are interconnected by means of a link 71 extending through a vertically elongated slot 72 in the head 61. Also, the lower ends of each cylinder communicate with the fluid pressure supply line 47 through the medium of flexible conduits 73, and the piston 74 in each cylinder is fixed to the head by means of a vertical rod 75 extending through the upper end of the cylinder. Thus, it will be noted that the pressure of the fluid at the undersides of the fixed pistons in the cylinders 23 tend to move the latter in a downward direction and this movement is transferred to the spider 16 by means of the rod 24 mounted for vertical sliding movement on the axis of the punch in a bore formed in the punch 75.

holder 32. As shown in Figure 3, the upper end of the rod bears against the link 71 intermediate the ends of the latter and the lower end of the rod has a bearing engagement with the central 5 portion of the spider, tending to move the latter in a downward direction. Inasmuch as the stripper ring 17 is secured to the spider as a unit therewith, it follows that this ring is urged toward the die 12 by the fluid under pressure admitted 10 to the cylinders 23.

The extent of downward movement of the stripper is determined by means of the ring 25 secured to the underside of the punch holder 32 by means of the stud bolts 77 and having the 15 lower end extending laterally inwardly to provide the projection 25'. As previously stated, the projection 25' cooperates with an annular shoulder 17' on the stripper ring 17 to hold the latter in assembled relation with the ram.

20 It will be noted from the foregoing that when the ram is in its uppermost position shown in Figure 1, the annular shoulder 17' on the stripper ring 17 is maintained into engagement with the inwardly extending projection 25' on the ring 25 by the action of the fluid in the air cylinders 23. Consequently, the stripper 15 moves downwardly as a unit with the ram into abutting engagement with the upper edge of the sheet metal blank A and continues this movement until the pressure 25 of engagement of the lower end of the blank A with the arcuate section of the die 12 exceeds the constant pressure acting on the stripper through the air cylinders 23. When this condition exists, the punch continues to move downwardly 30 into the blank relative to the stripper until the ring 17 abuts the undersurface 31 of the punch holder 32, whereupon the blank is positively moved downwardly around the arcuate surface of the die. It will, of course, be understood that at the 35 same time the punch 11 is being moved downwardly and serves to prevent deformation of the blank during the forming operation.

It is believed that the operation of the press is clearly set forth in the general description of 45 the apparatus contained in the introductory section of the specification and, accordingly, this operation will not be repeated at this time. It may be pointed out, however, that the apparatus requires a relatively small amount of power to 50 fashion the blank to the cup-shaped contour illustrated in the drawings, and also offers the possibility of forming relatively deep cupped elements without tearing, or otherwise marring the blank. As a consequence, the present invention 55 not only provides for appreciably reducing the size of the apparatus required to form relatively deep cupped elements from sheet metal, but also materially reduces the amount of waste.

60 What I claim as my invention is:

1. In a metal working machine, a die provided with a portion slidably receiving one end of a tubular blank and having an inwardly curved portion for flaring said end of the blank inwardly, 65 a member movable toward the die and slidably engageable with the inner surface of the blank to cooperate with the first named portion of the die to effectively support the side walls of the blank therebetween, and means effective upon 70 initial movement of the member toward the die to exert a yielding pressure on the blank sufficient to slide the first named end of the blank into the die toward the curved portion of the die and effective upon continued movement of the 75 member toward the die to positively move the

blank in said direction to flare the end of the blank along the curved portion of the die.

2. In a metal working machine, a die provided with a portion slidably receiving one end portion of a tubular blank and having an inwardly curved portion for flaring said end of the blank inwardly, a punch movable toward the die and slidably engageable with the inner surface of the blank to cooperate with the first named portion of the die to effectively support the cylindrical side walls 10 of the blank therebetween, a member surrounding the punch and engageable with the edge of the blank opposite the end aforesaid thereof, and compressible means acting upon said member tending to move the blank into the die toward 15 the curved portion of the latter.

3. In a metal working machine, a die provided with a portion slidably receiving one end of a tubular blank and having an inwardly curved portion for flaring said end of the blank inwardly, a punch movable toward the die and slidably engageable with the inner surface of the blank, a member supported for movement relative to the punch and surrounding said punch for engagement with the edge of the blank opposite 20 the end of the latter aforesaid, compressible means acting upon said member tending to move the blank into the die toward the curved end portion of the latter, and means effective when the punch has been moved to a predetermined 25 position within the blank for positively moving said member in a direction to move the end aforesaid of the blank along the curved portion of the die.

4. In a metal working machine, a die having 35 a portion adapted to receive one end of a tubular blank and having an inwardly curved portion for flaring said end of the blank inwardly, a punch movable toward the die and into the opposite end of the blank, a member supported 40 for movement relative to the punch and surrounding the latter for abutting engagement with the edge of the last named end of said blank, and compressible means effective upon movement of the punch in a direction toward the die to 45 exert a pressure on said member tending to move the tubular blank into the die toward the curved portion thereof.

5. In a metal working machine, a die having a portion adapted to receive one end of a tubular 50 blank and having an inwardly curved portion for flaring said end of the blank inwardly, a punch movable toward the die and into the opposite end of the blank, a member supported for movement relative to the punch and surrounding the 55 latter for abutting engagement with the edge of the last named end of said blank, and compressible means effective upon movement of the punch in the aforesaid direction to exert a pressure on said member tending to move the tubular blank into the die toward the curved portion 60 thereof, said compressible means effective to hold said member against movement with the punch upon return movement of the latter, whereby the blank is stripped from the punch by said 65 member.

6. In a metal working machine, a die having a portion receiving one end of a tubular blank and having an inwardly curved portion for flaring said end of the blank inwardly, a punch 70 movable toward and away from the die and dimensioned to extend into the tubular blank, a ring supported for movement relative to the punch and surrounding the latter for engagement with the edge of the tubular blank opposite 75

the end aforesaid thereof, compressible means effective upon initial movement of the punch into the blank to exert a pressure on the ring tending to move the blank into the die toward the curved portion thereof, means effective upon continued movement of the punch into the blank to positively move the ring with the punch and cause a corresponding movement of the blank into the die, said compressible means also operable to hold the ring into engagement with the blank upon return movement of the punch to strip the blank from the punch, and means effective upon completion of the stripping operation to move the ring as a unit with the punch.

7. In a metal working machine, a die having a portion adapted to receive one end of a tubular blank and having an inwardly curved portion for flaring said end of the blank inwardly, a punch movable toward the die into the tubular blank, a ram for actuating the punch, a member surrounding the punch and engageable with the edge of the blank opposite the end aforesaid thereof, a lost motion connection between said member and ram permitting relative movement of the member and punch, and compressible means exerting a pressure on said member in a direction toward the die.

8. In a metal working machine, a die having a portion adapted to receive one end of a tubular blank and having an inwardly curved portion for flaring said end of the blank inwardly, a punch movable toward the die into the opposite end of the blank and movable in the opposite direction away from the die, means effective upon initial movement of the punch into the blank to engage the edge of the last named end of said blank, compressible means acting on said means to urge the blank into the die in a direction toward the inwardly curved portion of said die and effective upon return movement of the punch to strip the blank from said punch, and means operating in timed relation to the stripping operation to eject the blank from the die.

9. In a metal working machine, a die having a portion adapted to receive one end of a tubular blank and having an inwardly curved portion for flaring said end of the blank inwardly, a punch movable toward the die into the opposite end of the blank and movable in the opposite direction away from said die, means effective upon movement of the punch into the blank to engage the edge of the last named end of the blank, compressible means acting upon the above named means to urge the blank into the die with said punch and effective upon return movement of the punch to eject the blank from said punch, and fluid pressure actuated means responsive to return movement of the punch to eject the blank from the die after the stripping operation.

10. In a metal working machine, a die having a portion adapted to receive one end of a tubular blank and having an inwardly curved portion for flaring said end of the blank inwardly, a punch movable toward the die into the opposite end of the blank and also movable in the opposite direction away from the die, a stripper ring surrounding the punch and engageable with the edge of the blank opposite the end aforesaid thereof, compressible means acting on the stripper ring to urge the blank into the die with the punch and effective upon initial return movement of the punch to strip the blank from said punch, means movable as a unit with the punch and engageable with the stripper ring subsequent to the stripping operation to return said ring with

the punch, and means operating in timed relation to return movement of the stripper ring to eject the blank from the die.

11. In a metal working machine, a die section having side walls adapted to slidably receive one end of a tubular blank and curved inwardly to flare said end of the blank, a cooperating die section supported in an opening in the die section aforesaid to form a continuation of the inner surfaces of the side walls of said die section, a punch movable toward the die into the tubular blank and also movable away from the die, means effective upon movement of the die into the blank to exert a pressure on the edge of the blank opposite the end aforesaid and to move said blank into the die with the punch, and means effective upon return movement of said punch to move the second die section into the first die section to eject the blank from the latter die section.

12. In a metal working machine, a die having a recess therein provided with an annular inner side wall surface curved inwardly at the base of the die, said inner side wall surface of the die having a diameter approximating the external diameter of a tubular blank and adapted to slidably receive one end of the blank, a punch movable toward the die into the opposite end of the blank and having an external diameter predetermined to slidably fit the inner surface of the blank, and means operating in timed relation to movement of the punch into the blank to exert a yielding pressure on the edge of the blank opposite the first named end thereof tending to force the blank into the die and to subsequently positively move said blank with the punch with a force sufficient to flare the first named end of the blank inwardly on the curved surface of the die.

13. In a metal working machine, a die having a recess for receiving one end of a tubular blank and having an inwardly curved portion for flaring said end of the blank inwardly, a punch holder movable toward and away from the die and having a recess in the surface thereof opposite the die, a punch positioned between the recess in the punch holder and the die for movement into the end of the blank opposite the end aforesaid, means for securing the punch to the holder to effect movement of the punch as a unit with the holder, a member supported in the recess of a punch holder for limited movement relative to the holder and punch, compressible means normally urging said member in a direction toward the die, and means carried by said member and engageable with the edge of the blank opposite the first named end of the latter.

14. In a metal working machine, a die having a recess for receiving one end of a tubular blank and having an inwardly curved portion for flaring said end of the blank inwardly, a member movable toward the die into the opposite end of the tubular blank, and means operating in timed relation to movement of said member into the blank to move the said end portion of the blank along the curved portion of the die, said die and member having annular surfaces cooperating to frictionally engage the inner and outer surfaces of the blank beyond the flared end of the latter to hold the blank against deformation during the operation of the curved portion of the die to flare said end of the blank.

15. In a metal working machine, a die provided with an annular surface telescopically receiving one end portion of a tubular blank with

the outer surface of the latter end portion of the blank in frictional contacting relation with the annular surface of the die and having an inwardly curved portion for flaring said end of the blank inwardly, a member movable into the opposite end of the blank in a direction toward the die and having an annular surface frictionally engaging the inner surface of the blank to cooperate with the annular surface of the die to firmly hold the side wall of the blank to its original diameter during the operation of the curved portion of the die to flare the end aforesaid of the blank inwardly, yieldable means responsive to initial movement of the member into the blank to engage the edge of the second named end of the blank and urge the blank along the annular surface of the die toward the curved portion of the latter, and means operating when the side walls of the blank are effectively engaged by the

annular surfaces of the die and member to positively move the blank in the aforesaid direction with sufficient force to cause the first named end of the blank to move along the curved portion of the die. 5

16. In a metal working machine, a die provided with a portion slidably receiving one end portion of a tubular blank and having an inwardly curved portion for flaring said end of the blank inwardly, means for moving said blank in a direction toward the curved portion of the die to flare the end aforesaid inwardly, and means movable into the opposite end of the blank in engagement with the side walls of the latter to cooperate with the first named portion of the die to maintain the tubular side walls of the blank cylindrical during the upsetting of the metal by said flaring means.

FRANK H. LE JEUNE.
